[57] CLAIM

The ornamental design for a card holder, as shown and described.

DESCRIPTION

FIG. 1 is a perspective view of a card holder according to the present invention, in a closed position;

FIG. 2 is a perspective view of the card holder of FIG. 1 in its open position and with a printable surface thereon;

FIG. 3 is a top plan view of the card holder of FIG. 1;

FIG. 4 is a bottom plan view of the card holder of FIG. 1;

FIG. 5 is a front elevation view of the card holder of FIG. 1;

FIG. 6 is a rear elevation view of the card holder of FIG. 1;

FIG. 7 is a left side elevation view of the card holder of FIG. 1 with the back flap closed;

FIG. 8 is a perspective view of the card holder of FIG. 1 in its open position showing the slidably removable lip removed bearing printed indicia thereon; and,

FIG. 9 is a left side elevation of the card holder of FIG. 1 with the back flap open.
